[57] CLAIM

The ornamental design for a combined clock and case, substantially as shown.

DESCRIPTION

FIG. 1 is a front elevational view of a combined clock and case showing my new design in the closed position;

FIG. 2 is a top plan view thereof;

FIG. 3 is a right side elevational view thereof, the left

side being a mirror image thereto;

FIG. 4 is a rear elevational view thereof;

FIG. 5 is a right front perspective view thereof in the

open position;

FIG. 6 is a front elevational view of another embodiment of my new design of FIGS. 1-5 in the closed position;

FIG. 7 is a top plan view thereof;

FIG. 8 is a right side elevational view thereof, the left

side being a mirror image thereto;

FIG. 9 is a rear elevational view thereof;

FIG. 10 is a right front perspective view thereof in the

open position.

FIG. 2.

FIG. 1.

FIG. 3.

FIG. 4.

FIG. 5.

FIG. 7.

FIG. 6.

FIG. 8.

FIG. 9.

FIG. 10.
